UNITED STATES PATENT OFFICE.

OSWALD B. CARSON, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR A DISPLAY-STAND.

58,567.

Specification for Design.

Patented July 15, 1919.

Application filed October 26, 1916. Serial No. 127,954. Term of patent $3\frac{1}{2}$ years.

To all whom it may concern:

Be it known that I, OSWALD B. CARSON, a citizen of the United States, residing at Southbridge, in the county of Worcester and State of Massachusetts, have invented a new and original ornamental Design for a Display-Stand, of which the following is a specification, reference being made to the accompanying drawings, forming a part thereof.

The figure represents a perspective view of my improved stand bearing suitable de-

vices for display and card for use in connection with the stand.

I claim:

The ornamental design for a display stand as illustrated.

In testimony whereof, I affix my signature in the presence of two witnesses.

OSWALD B. CARSON.

Witnesses:

E. M. HALVORSEN,
H. K. PARSONS.
